(57) **CLAIM**

The ornamental design for a hitch mount bicycle carrier platform rack, as shown and described.

DESCRIPTION

FIG. 1 is a top, front, and left-side perspective view of a hitch mount bicycle carrier platform rack showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

The broken lines in the drawings illustrate portions of the hitch mount bicycle carrier platform rack that form no part of the claimed design.
